A. J. BASSETT

OIL GAS APPARATUS

Filed May 31, 1924

UNITED STATES PATENT OFFICE.

ALVIN J. BASSETT, OF MILWAUKEE, WISCONSIN, ASSIGNOR TO THE BRUCE MACBETH ENGINE COMPANY, OF CLEVELAND, OHIO, A CORPORATION OF OHIO.

OIL-GAS APPARATUS.

Application filed May 31, 1924. Serial No. 717,071.

This invention relates to oil gas producers.

Objects of this invention are to provide an oil gas apparatus in which a greater economy and a quicker action results so that the gas apparatus 5 may be started with greater ease and speed than heretofore, and may continue to operate with an increased efficiency over gas apparatus previously constructed.

Further objects are to provide an oil gas apparatus in which the correct proportioning 10 of air and oil for maximum efficiency in gas making is maintained regardless of variation in demand for gas, and to provide an oil gas apparatus which is automatic and inherently 15 stable in its operation.

An embodiment of the invention is shown in the accompanying drawing, in which:

The single figure is a vertical sectional view 20 through the oil gas apparatus showing it as it appears when associated with the preheater for the air and the steam generator.

The oil gas apparatus comprises a retort provided with a main casing 1. This main casing is completely surrounded by insulating fire proof material 2 which is preferably carried in a metallic container 3 suitably supported, as illustrated. This casing is provided with an outlet portion 4 which contracts to the proper size for connection to the 30 inlet pipe 5 of the air preheater. The shell 1 supports a retort tube provided with an enlarged portion 6 providing a partial combustion chamber and with a rearwardly extending shell 7. This partial combustion chamber 35 has its forward end preferably lined with a relatively thick heat resisting wall 8, as shown. A retort feed tube 9 projects into the retort tube and is spaced from its forward end. This retort feed tube 9 is adapted to deliver 40 the air and oil to the retort, and to serve as a chamber in which partial combustion of the vaporized oil takes place before entering the retort tube 7, and it is therefore referred to in the claims as a partial combustion oil vaporizing feed tube.

The hot oil gases pass into the air preheater and pass downwardly through a central pipe 11 in the steam generator. This air preheater is provided with a surrounding shell 12 and 50 with an air inlet portion 13 adjacent its upper end. The air passes through the inlet portion 13 and downwardly between the shell 12 and the highly heated central pipe 10. From this point the heated air passes through 55 the air delivery pipe 14 which is preferably

embedded in the insulation of the retort. The air passes downwardly through the pipe 15 to the Venturi tube 16 within which the oil supply nozzle 17 projects.

It is preferable in this apparatus to provide an oil chamber 18 immediately adjacent the oil nozzle. This oil nozzle 17 is provided with a downwardly extending short tube 19 which dips into the oil in the chamber 18. A suitable type of needle valve 20 is provided for controlling the flow of oil under certain conditions and, if desired, a removable plug 21 may be provided for the oil chamber to give access thereto. This oil chamber is supplied through an oil pipe 22 and is provided with an overflow pipe 23 which extends to a point materially above the lower portion of the tube 19 and which terminates below the center line of the nozzle 17, as shown.

As illustrated in the drawing, it is preferable to provide the oil chamber and associated parts as a separate member bolted to the Venturi tube 16. This Venturi tube, it will be noted, is provided with a removable plug 24 for a purpose hereinafter to appear and is carried by the rear end plate 25 of the retort, a suitable heat insulating wall 26 being preferably provided on the inner side of this rear wall.

If desired, steam may be supplied the retort 85 through an inwardly extending pipe 27. This pipe is connected by means of the pipe 28 with the lower portion of the steam generator 29 such steam generator being preferably of the flash type.

It is apparent that the air may be either forced in through the opening 13 or that the delivery pipe 30 for the entire apparatus may be connected to a suitable suction device. In fact it is obvious that an internal combustion 95 engine could be connected to the pipe 30 and supply the requisite suction, it being, of course, understood that suitable coolers, scrubbers and other devices are interposed between the engine and the delivery pipe 30. If desired, a suitable pyrometer 31 may project into the retort tube 7 to indicate the 100 temperatures therein.

In starting the apparatus, the plug 24 is removed and the needle valve 20 opened 105 slightly and the oil and air are ignited at the opening provided by the removal of the plug 24. The amount of oil admitted is just sufficient for complete combustion, and this complete combustion rapidly heats up the 110

retort and the air preheater so that heated air is immediately supplied the apparatus. The plug 24 is reinserted and after the retort has attained the requisite temperature, the needle 5 valve is fully opened to permit a predetermined quantity of oil to flow into the apparatus in excess of that needed for complete combustion. The proportioning of the air and oil is attained by the proportioning of 10 the Venturi tube, oil nozzle, and air supply, so that maximum efficiency for producing gas from the oil is maintained irrespective of the load upon the apparatus.

In operation, it has been found that partial 15 combustion begins in the retort feed tube 9 and that further partial combustion and fixing of the gases takes place within the enlarged portion of the combustion chamber. When the gases have reached the outer end 20 of the tube 7 of the retort, they are completely fixed and no further change takes place. These heated gases pass rearwardly around the retort and through the discharge portion 25 4 to the air preheater and from thence to the steam generator.

The portion of the apparatus adjacent the rear end of the retort tube 7 is found to be the hottest part of the system and, if desired, steam may be admitted through the pipe 27 30 to increase the hydrogen content of the gases.

It is to be noted that although no constriction of the gases occurs, nevertheless the device provides an extremely long flame travel within the retort, such flame travel being 35 roughly three times the entire length of the retort, and it is to be noted also that this long flame travel is attained in a compact device.

It is to be noted also that the retort is a closed retort and completely enclosed by insulating material and is initially brought to the required temperature by heat applied in the inside, whereby fuel is conserved from the time of initiation of combustion through the gas making operation. So far as I know 45 this is a novel idea and one of the important features of my invention.

It has been found that this type of oil gas apparatus is unusually efficient, may be readily started and brought to the requisite 50 temperature within a very few minutes, and will continue to operate in a highly efficient manner for an indefinite period.

It will be seen that an oil gas apparatus has been provided which may be quickly started,

which will maintain a uniform and high 55 efficiency and which is compact and sturdy in construction.

Although the invention has been described in considerable detail, it is to be understood that the invention may be variously embodied and is, therefore, to be limited only as 60 claimed.

I claim:

1. An oil gas apparatus comprising a closed 65 retort, a retort tube having a closed end fixed to the forward end of said retort and spaced from the rear wall thereof, and having a rear open end in proximity to said rear wall of the retort, a partial combustion oil vaporizing feed tube extended through the rear wall of the retort into the open end of the retort tube and to a point within said retort tube such as to effect the desired partial combustion of the oil in said feed tube, means for feeding oil and air into the partial combustion oil vaporizing feed tube, and a gas outlet from said retort.

2. The combination specified in claim 1 in 70 which the retort tube is provided with an enlargement near its fixed end.

3. The combination specified in claim 1 in 75 which the exit opening for the gas is through the forward wall of the retort and outside of the retort tube, whereby the gases are compelled to pass along the outer wall of the retort tube.

4. A partial combustion oil gas generating apparatus comprising a closed retort; a partial combustion oil vaporizing feed tube intersecting one end wall of said retort and projected thereinto to a point adjacent the other end; means for feeding oil and air into the wall-intersecting end of said tube; a retort tube closed at one end, spaced from the walls of the retort and spaced from and surrounding said feed tube and receiving the partial combustion products from the inner end of said feed tube and discharging the fixed gases into the outer surrounding retort space adjacent the wall-intersecting end of said feed tube; and a gas outlet from the retort adjacent the closed end of the retort tube.

In testimony that I claim the foregoing I have hereunto set my hand at Milwaukee, in the county of Milwaukee and State of 105 Wisconsin.

ALVIN J. BASSETT.
